UNITED STATES PATENT OFFICE.

ROBERT HOE, OF POUGHKEEPSIE, NEW YORK.

WRENCH.

Application filed June 28, 1924. Serial No. 722,937.

This invention relates to improvements in wrenches of the general type comprising a rigid and a movable jaw connected by links. The especial objects of the invention 5 are to provide a spring mechanism for closing the wrench jaws that shall be more satisfactory than those now in use, and to provide means for locking the jaws in open position ready for engagement with the object to be gripped. Other features of the 10 invention will be hereinafter referred to.

For a full understanding of the invention, a detailed description of constructions embodying all the above features in preferred 15 and modified forms will now be given in connection with the accompanying drawings forming a part of this application, and the features forming the invention then be pointed out in the claims.

20 In the drawings—

Figure 1 is a side elevation of a wrench embodying the present improvements in their preferred forms, with the wrench jaws in inoperative position;

25 Figure 2 is an edge view thereof;

Figure 3 is a section on the line 3—3 of Fig. 1;

30 Figure 4 is a view similar to Fig. 1, with the jaws locked in open position and ready for engagement with the object to be gripped;

Figure 5 is a section on the line 5—5 of Fig. 4;

35 Figure 6 is a side elevation of a modified form of catch for locking the jaws in open position; and

Figure 7 is a section on the line 7—7 of Fig. 6.

Referring now to the drawings, the 40 numeral 10 indicates the stationary or rigid jaw on the end of the handle or shank 11, 12 being the swinging or movable jaw, and 13, 14 links arranged in pairs and pivoted to the side faces of the jaws 10, 12 to secure the 45 jaws movably together, the pivotal points of the links on the stationary jaw 10 preferably being arranged closer together than the pivotal points on the movable jaw, and the best results being obtained with substantially 50 the relative arrangement shown. To stop the closing of the wrench in the desired partially open position, and thus prevent unnecessary wear on the jaw teeth 15, a stop 55 16 on one or more of the links may be provided.

The present invention consists mainly in

providing an improved spring mechanism for exerting a closing pressure on the wrench jaws. To secure this result, a coiled spring is used, co-acting with the links in such a 60 manner that the jaws are closed by the coil tension tending to unwind the coil, and opened against the resistance of re-winding the coil, as distinguished from the pull coils or flat springs previously suggested. In the 65 preferred construction and as shown, a spring having a coiled portion 1 is mounted on a pin 2 positioned between the links 14 at a point approximately central of the link ends. The free end 3 of the spring 1, in 70 the arrangement shown, abuts against a pin 4 positioned at a point between the pin 2 and the ends of the links 14. The other free end 5 of the spring 1 abuts against the under 75 side of a pin 6 positioned intermediate the ends of the links 13. The coiling tension of 80 spring 1 is thus increased by the opening of the jaws and reacts to close the jaws by the unwinding of the coil, the tension increase and decrease depending upon the relative angle of the links and the position of the pins 2, 6 thereon, both of which may be varied. The free end 5 of spring 1 may be curved as shown, so that with the jaws in 85 inoperative position the abutment or pin 6 will lie at a lower point in the curved area, and thus, as the jaws are forced open, a cam action is produced by the incline on end 5 in co-operation with pin 6, and an increase 90 in the winding tension of the coiled portion 1. The pin 6 preferably is seated in lugs 7 formed on the inner edges of the links 13, although such lugs may be dispensed with and the pin 6 be mounted in holes formed in 95 the links as heretofore formed.

A coiled spring having its ends extended to co-operate with the wrench jaws and functioning as above described, is highly efficient as compared with a flat spring or a pull spring, because the spring action is practically uniform throughout. Such a spring is also longer lived than the ordinary pull or helical spring which is stretched or compressed each time the jaws are opened, and furthermore avoids the localized bending 100 common to a flat spring. The spring mechanism above described is cheap to manufacture, improves the appearance of the wrench, and the parts may be readily assembled or the spring replaced without difficulty.

110 The wrench thus far described may be conveniently used by laying the projecting

end of the movable jaw 12 against the object to be gripped and applying slight pressure on the handle 11, thus forcing the jaws apart against the winding up resistance of the 5 spring above described, so that the wrench will automatically adjust itself in position on such object. In the larger sizes of wrenches of this type, however, the spring tension on the jaws is usually quite heavy, 10 so that if the wrench jaw should slip in thus applying the wrench it might happen that the hand of the user would be caught and injured. To avoid this, and provide a simple and easily operable means for holding the 15 wrench jaws in open position, there is provided a lock, consisting, in the form shown in Figs. 1-4, of a lug 8 on the edge of the shank 11, the rear wall 9 of which is approximately at right angles to the shank or 20 handle and in such position thereon that when the jaws are forced to their extreme open position the coiled portion 1 of the spring on pin 2 will engage the wall 9 with sufficient friction to hold the jaws open. In 25 this connection it will be noted that the pin 2 is considerably smaller than the space within the coiled portion 1 of the spring, which provides for a slight play between this portion of the spring and the pin, so that 30 when the portion 1 of the spring comes into contact with the end of the lug 8 it may be displaced sufficiently to ride over the same and engage the wall 9 and act to hold the parts in position as shown in Fig. 4. Thus, 35 when the open jaws of the wrench are applied about the object to be gripped, a slight forward pressure of the thumb or finger on the rear of the movable jaw 12 or the links 14, will cause the spring portion 1 to be released from the lug 8, when the jaws will 40 snap shut on such object and thus avoid any possibility of injury to the hand of the user.

In Figs. 6 and 7 there is shown a modified form of catch which may, if desired, be substituted for that above described. A more positive lock is provided by this modified construction, in that the U-shaped trigger 18, which is mounted on pivot 19 extending through the shank 11, and on which the 45 trigger is arranged to rock, has a projecting portion 20 which is arranged to engage a notch 21 formed at the base of the links 14, when the jaws are in their extreme open position. Pressure on thumb piece 22 will rock 50 the trigger 18 so as to release the projection 20 from the notch 21 on the links 14, and permit the jaws to snap shut on the object to be gripped. A leaf spring 23, secured by rivet 24 or otherwise to the underside of the 55 thumb piece 22 may be provided, which normally presses against the edge of the shank 11 so as to cause the trigger to snap into locking engagement with the notch 21 when the jaws are pulled back to their extreme 60 open position.

Referring to Figs. 1 to 5, there is shown a removable plate 25 in which are formed the jaw teeth. While this removable plate is shown as applied to only the rigid jaw, it may, of course, be applied to either or both of the jaws. Preferably and as shown the plate 25 is provided with side flanges 26 which overhang the sides of the jaw member to which applied, and is also provided with a convex bottom surface arranged to occupy 70 a cavity in the wrench jaw of corresponding shape. The plate may be readily secured in position by a single rivet 27, which, due to the concavo-convex seating surfaces, will hold the same rigidly and securely in position. 75

This removable plate carrying the jaw teeth materially increases the life of the wrench because as the teeth become worn or broken a new plate may be readily attached 80 to the wrench jaw. It also enables the use of a higher grade of steel and consequently better tempering of the jaw teeth than would be the case where they are formed directly on the jaw member, due to the difficulty of 85 properly hardening and tempering such jaw portion while leaving the remainder of the jaw or handle comparatively soft.

It will be understood that the features of invention herein shown and described are 90 not limited to the exact form or arrangement of parts shown, but that modifications may be made therein while still retaining the invention defined by the claims.

What is claimed is:

1. A wrench comprising a fixed jaw, a movable jaw, links pivotally connecting the jaws, and a spring having a coiled portion mounted on one link and having its opposite ends extended and abutting respectively against the two links to secure the tightening of the coil by the opening movement of the jaws and close the jaws by unwinding pressure of the coil. 100

2. A wrench comprising a fixed jaw, a movable jaw, links arranged in pairs and pivotally connecting the jaws, a coiled spring mounted on and between one pair of said links and having ends extended and abutting against links of each pair to secure the tightening of the coil by the opening movement of the jaws and close the jaws by unwinding pressure of the coil. 110

3. A wrench comprising a fixed jaw, a movable jaw, links arranged in pairs and pivotally connecting the jaws, and a spring having a coiled portion mounted on a pin positioned between the rear links and having its ends extended and abutting respectively against each one of the pairs of links 115 for exerting a closing pressure on the wrench jaws. 120

4. A wrench comprising a fixed jaw, a movable jaw, forward and rear links pivotally connecting the jaws, and a spring hav- 125

ing a coiled portion mounted on the rear link and having its ends extended and abutting respectively against the forward and rear links for exerting a closing pressure on the wrench jaws.

5. A wrench comprising a fixed jaw, a movable jaw, links pivotally connecting said jaws, a spring co-operating with said links and normally tending to force the jaws together, and locking means for holding said movable jaw in open position.

6. A wrench comprising a fixed jaw, a movable jaw, links pivotally connecting said jaws, a spring co-operating with said links and normally tending to force the jaws together, and handle having a lug thereon arranged to co-operate with said spring to form a frictional catch to hold the wrench jaws open.

7. In a wrench, the combination with the 20 fixed and movable jaws, and front and rear links 13, 14, of coiled spring 1 mounted loosely on links 14, and a handle having fixed lug 8 co-acting with the spring coil to form a frictional catch.

8. In a wrench, the combination with the 25 fixed and movable jaws, and front and rear links 13, 14, of a spring having a coiled portion 1 mounted on links 14 with its ends 3, 5 held by the links, an abutment on link 13 30 for the free end 5 of such spring, said free end being formed to move over its link abutment to produce a cam action as the jaws are opened and thereby increase the winding tension of the coil 1.

35 In testimony whereof, I have hereunto set my hand.

ROBERT HOE.
